UNITED STATES PATENT OFFICE.

EUGENE M. SCOVILLE, OF MILWAUKEE, WISCONSIN, ASSIGNOR OF ONE-HALF TO FLOYD L. SWANBERG, OF PITTSBURGH, PENNSYLVANIA.

MULTIFEED PUMP.

Application filed October 1, 1925. Serial No. 59,766.

This invention relates in general to improvements in the art of fluid distribution, and relates more specifically to improvements in the construction and operation of 5 multiple feed pumps for delivering liquids such as oil in regulated quantities to a plurality of distribution lines or pipes.

An object of the invention is to provide improved pumping mechanism which is 10 simple in construction and efficient in operation.

Some of the more specific objects of the present improvement are as follows:—

To provide an improved multi-feed lubricator which is extremely compact in structure, and which is capable of automatically delivering accurately measured quantities of lubricant to a plurality of sources of utilization.

20 To provide an improved pump having several discharge lines, and means whereby the quantity of fluid delivered to any one of the discharge lines may be varied independently of the others.

25 To provide pumping mechanism comprising a capacity determining pump and a final discharge pump operating in series and controllable to alter the characteristics of the discharge, during normal operation 30 of the mechanism.

35 To provide a durable pump all parts of which are conveniently accessible for inspection and adjustment, and in which the actual conditions of operation are plainly visible at all times.

40 To provide other improvements in the details of construction and operation of fluid pumping and distributing mechanisms whereby the cost of construction thereof is reduced to a minimum and the efficiency is enhanced to a maximum.

45 Some of the novel features of pump and pump drive construction, disclosed but not specifically claimed herein, form the subject of copending applications Serial No. 567,064, filed June 9, 1922, and Serial No. 589,748, filed September 22, 1922.

50 A clear conception of the various novel features of the present improvement and of the operation of devices constructed in ac-

cordance with the invention, may be had by referring to the drawings accompanying and forming a part of this specification, in which like reference characters designate the same or similar parts in the various 55 views.

Fig. 1 is a transverse vertical section through an improved multi-feed lubricator, the section being taken along the irregular line A—A of Fig. 3.

60 Fig. 2 is a side elevation of the multi-feed lubricator, a portion of the main casing having been broken away in order to more clearly disclose internal structure.

Fig. 3 is a partial top view of the multi-feed lubricator, some of the parts having been removed for the sake of clearness.

65 The improved multi-feed lubricator specifically illustrated in the drawing comprises generally a main casing 2 forming an oil supply chamber 45; a sheet metal cover 18 enclosing the top of the casing 2; a pump frame 7 detachably associated with the cover and having a vertical tapered bore 33 formed centrally therein; an intermittently rotatable pump cylinder 6 coaxing with the bore 33 of the frame 7; a two diameter pump plunger 5 reciprocable within the cylinder 6 and cooperable with the cylinder interior to form upper and 70 lower displacement chambers 29, 22; mechanism including horizontal drive shaft 3 supported in combined stuffing boxes and bearings 48, 49 associated with the casing 2, for rotating the cylinder 6 and for reciprocating the plunger 5; and a plurality of independent feed pipes or lines 8 communicating with conduits 30 formed in the frame 7.

75 The main casing 2 is provided with a transparent gage 38 for indicating the level of the oil within the chamber 45, and also has a coil 39 therein for controlling the temperature of the oil. Fresh oil may be supplied to the chamber 45 through a strainer 90 46 which is normally enclosed and retained in position by a removable cover 53, and the oil may be withdrawn from the chamber 45 by removing a drain plug 42. The sheet metal cover 18 is detachably secured to the 95 100

upper end of the casing 2, and besides providing a direct support for the frame 7, the cover 18 also supports the strainer 46 and the auxiliary cover 53.

5 The pump frame 7 is provided with an annular series of eight recesses 43 surrounding the tapered bore 33 therein, and also has two series of segregated conduits 30, 24 formed therein. The conduits 30 of the one 10 series have their inner ends connected to the adjacent recesses 43, and have their outer ends screw-threaded to receive coupling elements 32 which connect the pipe lines 8 to the top of the frame 7. The conduits 24 are 15 variable in cross-sectional area by virtue of flow control needles 17 having screw-thread coaction with the frame 7, and which are adjustable from the exterior of the mechanism. The intermittently rotatable pump 20 cylinder 6 has a central through bore of two diameters, the upper extremity of which is sealed by means of a stem or plug 55 having a central passage 26 therein. A nozzle 27 which is secured to the upper end of the 25 plug 55 and extends laterally therefrom, has a central passage communicating with the plug passage 26 and formed to deliver liquid downwardly and centrally toward the successive recesses 43 during intermittent rotation of the pump cylinder. A retaining collar or ring 34 secured to the plug 55 adjacent to the upper end of the cylinder 6, coacts with the upper surface of the frame 7. A transparent bell-shaped cap 9 normally 30 encloses the plug 55, nozzle 27 and the recesses 43, the cap 9 being detachably retained in proper position by means of oppositely disposed springs 31 coacting with inclined upper surfaces of lugs projecting laterally 35 from the cap 9. The passage 26 within the plug 55 is communicable at the bore 33 with the successive outwardly directed passages 25 formed in the frame 7, during rotation of the cylinder 6 and plug 55, the passages 25 40 communicating with the conduits 24 at the needles 17. The medial portion of the pump cylinder 6 is provided with a vertical conduit 23 the upper end of which is communicable at the bore 33 with the successive inner ends of the conduits 24, during intermittent rotation of the cylinder. 5.

The vertically reciprocable pump plunger 5 has an upper end of reduced diameter co-operating with the cylinder 6 and with the 55 plug 55 to form the upper displacement chamber 29, and has a medial shoulder co-operating with the inner surfaces of the cylinder 6 to form the lower annular displacement chamber 22. A conduit 21 formed 60 within the lower portion of the plunger 5 communicates at its upper end directly with the displacement chamber 22, and has its lower end in open communication with the suction pipe 54. The suction pipe 54 is attached to the lower enlarged extremity 40

of the plunger 5, and carries a strainer 41 at its lower end. A plunger retainer 19 secured to the frame 7 coacts with the opposite sides of the pipe 54 to positively prevent rotation of the plunger 5 about its central axis, while permitting free vertical reciprocation of the plunger 5. A helical compression spring 20 embracing the lower portion of the rotary cylinder 6 coacts with the enlarged plunger extremity 40 and with an 70 enlargement at the medial portion of the cylinder 6, this spring at all times exerting an upward pressure against the cylinder 6 and forcing the same into the tapered bore 33 of the frame 7, and simultaneously exerting a downward pressure upon the plunger 5.

The flow of fluid through the improved pumping mechanism is controllable by means of a series of spring pressed ball valves each of which is conveniently removable. The suction valve 12 disposed within the strainer 41 controls the admission of oil from the chamber 45 to the lower displacement chamber 22 through the pipe 54 and the conduit 90 21. The discharge valve 13 mounted within the cylinder 6 controls the delivery of oil from the chamber 22 to the conduit 23 and to the return or by-pass valve 14 which is disposed within a fitting 44 carried by the cylinder 6. A suction valve 15 disposed in each of the conduits 30 directly below its corresponding recess 43, controls the communication between the recesses 43 and the upper displacement chamber 29 through the 100 port 28 in the cylinder 6. A final discharge valve 16 disposed in each of the conduits 30 beyond the valve 15 therein, controls the delivery of oil to the corresponding pipe line 8. It will be noted that the valves 13, 14, 15, 105 16 may be of identical construction thus making them interchangeable.

The mechanism for intermittently rotating the cylinder 6 about the reciprocating plunger 5 comprises a toothed element 10 110 detachably secured to the medial enlarged portion of the cylinder 6 by means of screws 35, and an actuator arm 11 secured to the drive shaft 3 and intermittently engageable with the successive teeth of the element 10. 115 The mechanism for reciprocating the pump plunger 5 within the cylinder 6 comprises an actuating cam 4 secured to the drive shaft 3 adjacent to the arm 11 and engageable with the lower enlargement 40 of the plunger 5. The portion of the shaft 3 within the casing 2 and adjacent to the end of the hub of the arm 11 is embraced by a sleeve 50 for preventing end displacement of the arm 11 and of the cam 4. One end of the shaft 3 120 may be provided with a crank 51 or other means for imparting continuous rotary motion to the shaft 3. The opposite end of the shaft 3 may be provided with a lever 52 or other means for imparting intermittent os- 125 130

cillatory motion to a pawl 47 which is rotatable about the shaft 3. The pawl 47 is engageable with side teeth of a ratchet wheel 36 which is attached to the shaft 3 directly adjacent to the cam 4. Reverse rotation of the ratchet wheel 36 and of the shaft 3 is prevented by a leaf spring 37 which is engageable with peripheral teeth of the wheel 36.

5 During normal operation of the multi-feed lubricator, the drive shaft 3, cam 4 and arm 11 may be rotated continuously by means of the crank 51 or the lever 52, or intermittently by oscillating the lever 52, thereby causing simultaneous reciprocation of the plunger 5 and intermittent rotation of the cylinder 6 and of the elements carried thereby. When the plunger 5 moves downwardly, the displacement chambers 22, 29 are enlarged thus causing the suction valve 12 to open and to admit a definite quantity of oil from the chamber 45 to the conduit 21 and chamber 22, and also causing one of the suction valves 15 to open and to admit a definite quantity of oil from the corresponding recess 43 to the corresponding conduit 30 in advance of the final discharge valve 16 therein. As the plunger 5 is forced upwardly by the advancing cam 4, the excess oil previously drawn into the chamber 22 is forced past the valve 13 and a portion of the displaced oil is urged through the conduits 23, 24 and one set of the passages 25, 26 to one of the recesses 43, while the excess oil which is not permitted to traverse such course by virtue of the setting of the corresponding needle 17, is returned directly to the supply chamber 45 past the by-pass valve 14 in the fitting 44. Simultaneously with such displacement of the oil by the lower portion of the plunger 5, the upper end of the rising plunger 5 acts upon the oil filled chamber 29, port 28 and conduit 30 and forces a definite quantity of the confined oil past the corresponding final discharge valve 16 into one of the distribution lines 8. After one complete reciprocation of the plunger 5 has been thus completed, the arm 11 secured to the rotating shaft 3, becomes effective to produce partial rotation of the cylinder 6 through one eighth of a circle, whereupon the plunger 5 is again reciprocated to repeat the cycle and to force a predetermined quantity of oil into the next feed line 8. It will be apparent that as the rotation of the shaft 3 continues, the plunger 5 is intermittently reciprocated and the cylinder 6 is alternately intermittently rotated through an eighth of a revolution, and the various elements automatically function to deliver accurate quantities of oil to each of the distribution lines 8 in succession.

If it is found desirable to vary the quantity of oil which is delivered to any one of the lines 8, such variation may be quickly

effected by adjusting the corresponding needle 17. By entirely closing one or more of the conduits 24 with the aid of the needles 17 therein, the delivery of oil to the corresponding lines 8 may be entirely stopped. When the conduits 24 are thus closed off, all of the oil displaced from the lower chamber 22 is returned directly to the supply chamber 45 past the by-pass valve 14.

The operation of the apparatus is plainly visible at all times by virtue of the transparent cover 9 and of the gage 38. The cover 9 may be quickly removed to permit access to the recesses 43, the plug 55 and the nozzle 27, by merely urging the springs 31 away from the tapered projections on the cover 9 and these projections assure tight closure of the cover 9. The pipe lines 8 may be disconnected from the frame 7 at will by releasing the couplings 32 and the entire frame 7 and the elements carried thereby are readily removable from the cover plate 18 and from within the casing 2 without disturbing the driving mechanism. When the frame 7 is removed from the cover plate 18, the plunger 5 and the spring 20 are freely removable from the cylinder 6. Upon removal of the nozzle 27 and the retaining collar 34, the cylinder 6 is freely removable from within the bore 33 of the frame 7, thus permitting rapid dismantling of the entire structure.

It will also be observed that while the cylinder 6 is rotatably about its longitudinal axis, it is normally prevented from moving along its axis by the spring 20. The plunger 5 which is reciprocable within the cylinder 6 by the spring 20 and the cam 4, is positively prevented from rotating about the cylinder axis by means of the element 19. While the invention has been illustrated as being applied to an eight feed structure, it is obviously capable of application to mechanisms having any number of feeds.

It should be understood that it is not desired to limit the invention to the exact details of construction and operation herein shown and described for various modifications within the scope of the claims may occur to persons skilled in the art.

It is claimed and desired to secure by Letters Patent:—

1. In combination, a frame having a bore and a plurality of independent fluid distributing ports terminating directly at said bore, a cylinder rotatably associated with said bore and having a port formed to establish direct and independent communication between the interior of said cylinder and said frame ports in succession, a plunger reciprocable within said cylinder, and means for moving said plunger relative to said cylinder only while the latter is at rest and when said cylinder port is in full open communication with one of said frame ports.

2. In combination, a frame having a tapered bore and a plurality of independent fluid distributing ports radiating from and terminating directly at said bore, a cylinder 5 rotatably associated with said bore and having a radial through port formed to establish direct and independent communication between the interior of said cylinder and said frame ports in succession, a plunger reciprocable within said cylinder, means for moving said plunger in one direction and for simultaneously urging said cylinder against said bore, and means for moving said plunger in the opposite direction only while said 15 cylinder is at rest and when said cylinder port is in full open communication with one of said frame ports.

3. In combination, a frame having a bore and a plurality of independent fluid distributing ports terminating at said bore, a cylinder rotatably associated with said bore and having a port formed to establish direct and independent communication between the interior of said cylinder and said frame 20 ports, a valve for controlling admission of fluid to said cylinder through each of said frame ports, a valve for controlling discharge of fluid from said cylinder through each of said frame ports, a plunger reciprocable within said cylinder, and means for moving said plunger in opposite directions while said cylinder is at rest to effect actuation of each set of said valves.

4. In combination, a frame, a cylinder rotatably associated with said frame, a gear secured to said cylinder and surrounding the axis thereof, a plunger reciprocable within said cylinder, a rotary shaft extending transversely across said axis adjacent to said gear and an end of said plunger, a cam carried by said shaft and cooperable with said plunger to move the same longitudinally of said cylinder, and a member carried by said shaft and having a tooth cooperable with the teeth of said gear to intermittently rotate said cylinder.

5. In combination, a frame, a cylinder rotatably associated with said frame, a gear secured to said cylinder and surrounding the axis thereof, a plunger reciprocable within said cylinder, a rotary shaft extending transversely across said axis adjacent to said gear and an end of said plunger, a cam carried by said shaft and cooperable with said plunger to move the same along said cylinder in one direction, a spring coacting with said cylinder and with said plunger to move the latter in the opposite direction, and a member carried by said shaft and having a tooth cooperable with the teeth of said gear to intermittently rotate said cylinder.

6. In combination, a frame having a bore and a plurality of independent fluid distribution ports terminating directly at said bore, said ports having like circular cross-

section at said bore and being spaced apart less than a port diameter, a cylinder rotatably associated with said bore and having a port formed to establish direct and independent communication between the interior of said cylinder and said frame ports in succession, a plunger reciprocable within said cylinder, and means for moving said plunger relative to said cylinder only when said cylinder port is in full open communication with one of said frame ports.

7. In combination, a frame, a plurality of independent fluid distribution lines associated with said frame, a cylinder rotatably associated with said frame and having a port formed to establish independent communication between the interior of said cylinder and said lines, and a pair of aligned plungers movable longitudinally within said cylinder, one of said plungers being effective to supply a quantity of fluid to each of said lines in succession and the other being adapted to force said fluid through said lines.

8. In combination, a frame, a plurality of independent fluid distribution lines associated with said frame, a cylinder rotatably associated with said frame and having a port formed to establish independent communication between the interior of said cylinder and said lines in succession, a pair of aligned plungers reciprocable within said cylinder, one of said plungers being effective to supply a definite quantity of fluid to each of said lines in succession and the other being adapted to force said fluid through said lines, and means for varying the quantities of fluid delivered to said lines by said supply plunger.

9. In combination, a frame, a plurality of independent fluid distribution lines associated with said frame, a cylinder rotatably associated with said frame and having a port formed to establish independent communication between the interior of said cylinder and said lines in succession, a pair of aligned plungers reciprocable within said cylinder, one of said plungers being effective to supply a quantity of fluid to each of said lines in succession and the other being adapted to force said fluid through said lines, and means for moving said plungers relative to said cylinder only when said cylinder is at rest and while the port thereof is in full open communication with one of said lines.

10. In combination, a frame, a plurality of independent fluid distribution lines associated with said frame, a cylinder rotatably associated with said frame and having a port formed to establish independent communication between the interior of said cylinder and said lines in succession, a pair of aligned plungers reciprocable within said cylinder, one of said plungers being effective

to supply a definite quantity of fluid to each of said lines in succession and the other being adapted to force said fluid through said lines, means for varying the quantities of fluid delivered to said lines by said supply plunger, and means for moving said plungers relative to said cylinder only when said

cylinder is at rest and while the port thereof is in full open communication with one of said lines.

In testimony whereof, the signature of the inventor is affixed hereto.

EUGENE M. SCOVILLE.
